UNITED STATES PATENT OFFICE.

EUGENE C. KINNEAR, OF SEATTLE, WASHINGTON, ASSIGNOR TO ANAKIN LOCK WORKS,
OF CHICAGO, ILLINOIS, A CORPORATION OF ILLINOIS.

LOCK.

Application filed May 7, 1920. Serial No. 379,454.

To all whom it may concern:

Be it known that I, EUGENE C. KINNEAR, a citizen of the United States, residing in Seattle, in the county of King and State of Washington, have invented a new and useful Improvement in Locks, of which the following is a specification.

This invention relates in general to safety appliances for safes, vaults and the like and has more particular reference to the provision of a safety appliance for preventing opening of the safe or vault door after the combination or time locking mechanism has been broken or blown away or otherwise 15 forced from its normal position.

A principal object of the present invention is the provision of a device of this character for insuring against the withdrawal of the locking bolts usually provided for 20 the locking of the safe or vault door when the means normally holding said bolts against retraction becomes no longer operative.

Another highly important object of the 25 invention is the provision of means which will remain operative after the time locking mechanism or combination mechanism is disturbed for holding the safe or vault door securely locked at a number of points arranged in spaced relation along the door edge.

Another important object of the invention is the provision of a safety device of the character described which may be arranged 30 on the inner side of the door, and at any desired height and in such manner that its location cannot be detected from without the vault or safe. My invention contemplates in this connection the provision of a safety device which cannot be tampered with by persons not intimately acquainted with the 40 position given said device in the particular safe in which it is installed.

A further object of the invention is the provision of a device of the character described, which may be readily installed without disturbing any of the parts usually provided on safe and vault doors, and which will not involve the utilization of any locking bolts in addition to those already on the 45 safe door.

Numerous other objects and advantages of the present invention will be readily apparent as the invention is better understood 55 from the following description when con-

sidered in connection with the accompanying drawing illustrating a preferred embodiment thereof.

Referring to the drawings—

Figure 1 is a rear elevation of a safe door 60 equipped with my present invention;

Fig. 2 is a similar view on an enlarged scale of the time or combination mechanism and the safety lock in which my invention is embodied, the rear cover plate of the latter having been removed;

Fig. 3 is a view similar to Fig. 2 with the parts differently arranged; and

Fig. 4 is a section taken substantially on the line 4—4 of Fig. 2. 70

For the purpose of illustrating my present invention I have shown on the drawings a safe door 11 of any usual or preferred construction and suitably hinged in a casing or frame 12 by hinges 13. In the present instance this door is provided with inwardly extending flanges 14 in which are slidably mounted locking bars or bolts 15 which may be projected into a locking flange 16 on the door frame. The bolts 15 are fast to a common control bar 17 which is adapted to be moved latterly by any suitable manually operable means or otherwise. 75

Reference character 18 indicates the combination or time locking mechanism and in 80 accordance with the usual practice this time locking or combination mechanism is provided with the usual plunger 19 adapted to prevent unlocking movement of the control member or carrying bar 17. By means of 85 the plunger 19, the control member 17 may be set in its operative position and the mechanism generally indicated by the reference character 18 may, therefore, be referred to as a setting mechanism. 90

It will be readily appreciated that if the mechanism 18 be broken or blown away by explosion or become otherwise dislodged, the control member 17 may be moved to unlock the safe or vault and this is the 100 usual procedure in surreptitious opening of such doors. My invention contemplates the provision of means for preventing this movement of the control bar under such conditions and circumstances. This means 105 comprises an auxiliary bolt or plunger 21 which is automatically moved into position behind the control member upon dislodgment of the combination or time locking mechanism. The plunger 21 has a shank 110

which is of angular section throughout a part 22 adjacent the plunger head and circular in section therebeyond as indicated at 23. The plunger extends through an opening 24 in the front of an enclosing wall 25 which opening is of a shape corresponding to the sectional shape of part 22. The round portion 23 of the shank extends into a guiding sleeve or cylinder 26 located within the side wall 25. A spring 27 is provided behind the shank and exerts pressure on the plunger, tending to move it into locking position. The plunger is held retracted by a bell crank pivoted at 28 and having one arm 29 engaged in a slot 31 in the shank and having the other arm 32 connected by a link 33 with an arm 34 of a second bell crank pivoted at 35 in a bracket 36 which is mounted upon the safe door 11 in appropriate location. The other arm 37 of this second bell crank extends down behind the combination or time locking mechanism and through the extremity of the arm 37 a set screw 38 is positioned, this set screw taking into a threaded aperture 39 in the time locking or combination mechanism.

The wall 25 is the peripheral wall of a housing for the plunger and its controlling mechanism and extends up from a base 41. A bracket 42 is provided to extend rearwardly from this base 41 and in this bracket is fixed the forward end of the sleeve 26. The side wall 25 and base 41 constitute parts of a housing which may be fastened in an appropriate position upon the inner side of the safe door by machine screws extending through the base 41 and into, but preferably not through, the safe door.

Should the time locking or combination mechanism become dislodged it will be manifest that resulting movement of the two bell cranks and the link 33 will withdraw the arm 29 from latching position and permit the plunger 21 to be moved out by the spring 27 from the position shown in Fig. 2 to the position shown in Fig. 3, in which position it is arranged to prevent unlock ing movement of the control bar.

I provide a hollow boss 51 within the housing, and within this boss a lock or latch 52 is pressed outwardly by a spring 53 against the shank of the plunger. When the plunger is retracted this latch bears upon the angular part of the shank 22 and when the plunger is extended drops in behind the part 23 and prevents return movement of the plunger.

Since by using a link 33 of appropriate length the housing of the safety device may be located at any particular position and by changing the length of the link 33 this position may be altered or be different in different safes and on this account the position of the plunger 21 may not be deter-

mined from without the safe so that blowing away of the safety device is rendered difficult if not impossible.

It is thought that the invention and many of its attendant advantages will be apparent from the foregoing without further description and it will be manifest that various changes may be made in the form, construction and arrangement of the parts without departing from the spirit and scope of the invention or sacrificing all of its material advantages, the form hereinbefore described being merely a preferred embodiment thereof.

I claim:

1. A lock for safe doors and the like, comprising in combination: a plurality of locking bars or bolts, a control member therefor and simultaneously moving them into and out of operative position, a normally operable setting mechanism for said control member, means projectable into locking contact with said control member to prevent movement thereof when said setting mechanism is disarranged, and pivoted locking means normally preventing said projectable means from being moved into contact with said control member.

2. A lock for safe doors and the like, comprising in combination: a plurality of locking bars or bolts, a control member therefor and simultaneously moving them into and out of operative position, a normally operable setting mechanism for said control member, a bolt adapted to be projected into contact with said control member for holding same against movement from locked position when said setting mechanism is disarranged, and a pivoted locking lever normally engaging said bolt and operative to permit said bolt to be projected into contact with said control member.

3. A lock for safe doors and the like, comprising in combination: a plurality of locking bars or bolts, a control member therefor, a normally operable setting mechanism for said control member, and a device normally arranged in inoperative position and projectable upon bodily movement of said setting mechanism into position behind said control member, pivoted locking means normally preventing said device from being projected into position behind said control member, and means for positively engaging said device after it is projected to prevent said device from being withdrawn from engagement with said control member to permit withdrawal of said locking bolts.

4. A lock for safe doors and the like, comprising in combination, a plurality of locking bars or bolts, a control member therefor, constituting the normal bolt-carrying bar, a normally operable setting mechanism for said control member, and a plunger spring pressed toward a position preventing with-

- drawal of the locking bars, a latch adapted to engage said plunger and normally held in operative position maintaining said plunger retracted, said latch being withdrawn 5 from said locking engagement with said plunger upon movement of the setting mechanism to release said plunger and permit it to move into position obstructing the unlocking movement of said control bar.
- 10 5. A lock for safe doors and the like, comprising in combination, a plurality of locking bars or bolts, a control member therefor, a normally operable setting mechanism for said control member, and a plunger spring 15 pressed toward a position preventing withdrawal of the locking bars, a latch normally held in operative position maintaining said plunger retracted, said latch being withdrawn upon movement of the setting mechanism 20 to release said plunger and permit it to be moved into position obstructing the unlocking movement of said control bar, and a second latch for holding said plunger in the position last mentioned.
- 25 6. A lock for safe doors and the like, comprising in combination a plurality of locking bars or bolts, a control member therefor, a normally operable setting mechanism for said control member, and a normally inoperative auxiliary locking mechanism comprising a locking plunger having a recess in 30 a portion thereof, a latch normally engaged in said recess and holding the plunger retracted, a jointed connection between said latch and said setting mechanism and fixedly secured to the latter whereby the latch is released by disarrangement of said setting mechanism and means for projecting and holding said plunger in locking engagement 35 with said control member upon release of said latch.
- 40 7. A lock for safe doors and the like, comprising in combination a plurality of locking bolts, a carrying bar in which said bolts are mounted, a main locking mechanism for normally holding said carrying bar in posi- 45 tion with the bolts locking the door, a normally inoperative auxiliary locking device projectable into engagement with said carrying bar upon disturbance of said main locking mechanism, and a pivoted connection rigidly secured to the main locking mechanism and normally holding said auxiliary locking device inoperative, said connection being immovable except upon abnormal 50 movement of said main locking mechanism.
8. A lock for safe doors and the like, comprising in combination a plurality of locking bolts, a carrying bar in which said bolts are mounted, a main locking mechanism for 55 normally holding said carrying bar in position with the bolts locking the door, a normally inoperative auxiliary locking device projectable into engagement with said carrying bar upon disturbance of said main locking mechanism, and a connection rigidly secured to the main locking mechanism and normally holding said auxiliary locking device inoperative, said connection being jointed and including a replaceable member, the 60 length thereof being variable in accordance with the length of the replaceable member employed.
9. A lock for safe doors and the like, comprising, in combination, a plurality of locking bars or bolts conjointly movable in the fastening and releasing of the safe door, a control member therefor, a normally operable setting mechanism for said control member and adapted when set to prevent operation of said control member, a housing 65 mounted behind the door, a normally retracted member movable in the direction of the bolts and in said housing after the setting mechanism has been tampered with, pivoted means operative to permit said movement of said normally retracted member, and a lock within said housing released as a result of tampering with the setting 70 mechanism for preventing movement of said movable member.

EUGENE C. KINNEAR.
